UNITED STATES PATENT OFFICE

JOHN G. HUNTER, OF COLUMBUS, OHIO

DESIGN FOR A COMBINED TELEPHONE STAND AND TELEPHONE DIRECTORY SECRETARY

Application filed July 21, 1932. Serial No. 44,398. Term of patent 14 years.

To all whom it may concern:

Be it known that I, JOHN G. HUNTER, a citizen of the United States, residing in Columbus, in the county of Franklin and State of Ohio, have invented a new, original, and ornamental Design for Combined Telephone Stand and Telephone Directory Secretary, of which the following is a specification, reference being had to the accompanying drawing, forming part thereof.

The figure is a perspective view of a combined telephone stand and telephone directory secretary showing my invention.

I claim:

The ornamental design for a combined telephone stand and telephone directory secretary, substantially as shown.

JOHN G. HUNTER.
